(57) **CLAIM**

The ornamental design for packaging for a wound therapy system, as shown and described.

DESCRIPTION

FIG. 1 is a top, front, and left side perspective view of a packaging for a wound therapy system showing my new design in a closed configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top, front, and left side perspective view of the packaging for a wound therapy system of FIG. 1 in a partially open configuration.

FIG. 9 is a front elevation view of the packaging for a wound therapy system of FIG. 1 in a fully open configuration;

FIG. 10 is a rear elevation view thereof;

FIG. 11 is a right side elevation view thereof;

FIG. 12 is a left side elevation view of the packaging of FIG. 1 in a fully open configuration.

FIG. 13 is a top plan view thereof; and,

FIG. 14 is a bottom plan view thereof.

The broken lines in the drawings depict unclaimed subject matter and form no part of the claimed design.

1 Claim, 13 Drawing Sheets

Related U.S. Application Data

a continuation of application No. 29/492,878, filed on Jun. 3, 2014, now Pat. No. Des. 758,851.
